Fig 2

Fig 3

FIG. 1 is a view in side elevation of an optical illusion puzzle showing my new design.

FIG. 2 is a bottom plan view of the device as shown in FIG. 1; and

FIG. 3 is a view in end elevation.

The view in end elevation at each end is identical. The view in side elevation on the side opposite FIG. 1 is a mirror image, without the rectangular opening. The top plan view opposite the bottom plan view shown in FIG. 2 is identical, without the opening.

I claim:

The ornamental design for an optical illusion puzzle, as shown and described.
